UNITED STATES PATENT OFFICE.

JAMES H. McCAFFREY, OF BUFFALO, NEW YORK.

FOLDING RULE.

Application filed December 21, 1923. Serial No. 681,949.

To all whom it may concern:

Be it known that I, JAMES H. McCAFFREY, a citizen of the United States, residing at Buffalo, in the county of Erie and State of New York, have invented new and useful Improvements in Folding Rules, of which the following is a specification.

This invention relates to the class of folding or extension rules in which the sections are foldable laterally or edgewise upon one another and provided with resilient means for automatically locking them both in their folded and unfolded positions.

The object of the invention is the improvement of the lock joints of the rule-sections with a view of rendering them neat, compact, firm and reliable, while at the same time permitting the sections to be easily unlocked or turned from one position to another.

In the accompanying drawings:

Figure 1 is a perspective view of an extension rule embodying the invention. Figure 2 is an enlarged longitudinal section of one of the joints, showing the rule-sections fully unfolded. Figure 3 is a similar section, showing the rule-sections, partly unfolded to correspond to the position illustrated by dotted lines in Fig. 1. Figures 4 and 5 are cross sections on the correspondingly numbered lines in Fig. 2. Figure 6 is an edge view of one of the rule-sections. Figures 7 and 8 are perspective views of the joint-plates, respectively.

Similar characters of reference indicate corresponding parts in the several views.

10 and 11 indicate adjoining sections of the rule which are graduated as usual and pivotally united by a transverse rivet 12. 40 Between the pivoted overlapping end portions of the sections are interposed a pair of joint-plates 13 and 14, which are secured to the respective sections by any suitable means and stamped of a suitable resilient material, 45 such as hard spring brass. In the preferred construction shown, each plate is provided at its side edges with flanges 15 which embrace the beveled edges of the companion rule-section which is recessed to receive the flanges 50 and form a flush joint.

Each joint plate has a central opening 16 for the passage of the rivet or pivot 12, and one of the plates is provided on opposite sides of said opening with a pair of studs or teats 17 arranged to interlock with a corresponding pair of holes or sockets 18 in the

other plate, when the sections are turned on each other to their fully folded or unfolded position. For this purpose, the complementary locking studs and openings are arranged in a line extending centrally and lengthwise of the plates and are located equidistant from the pivot 12. As shown in Fig. 6, the joint plates and the corresponding end portions of the rule-sections are preferably arched lengthwise, so that when the rule is fully folded or unfolded, the plates are practically flattened out, placing them under tension and offering frictional resistance to the folding and unfolding movements of the rule-sections. If desired, the plates may also be arched crosswise to a slight degree.

Surrounding the pivot-hole of each plate is a hollow, comparatively shallow boss or dished portion 19, preferably of circular form. The opposing bosses face each other with their concave sides and form springs which supplement the action of the arched joint plates, allowing the locking studs to snap into and rise out of the locking openings, in folding and unfolding the rule sections. When the studs leave the openings and ride up on the face of the opposing plate, the bosses 19 are deflected or drawn toward each other, as shown in Fig. 3, the degree of their deflection being exaggerated for the sake of clearness. The bosses spring back to their normal position the moment the sections come into alignment and the studs snap into the openings, as illustrated in Fig. 2.

As shown, the headed ends of the pivot pass loosely through openings 20 of the rule sections and the head at one end of the pivot and the washer 12^a at the other end bear directly against the backs of the bosses 19, respectively.

To facilitate the locking action of the rule-sections, the bearing faces 17^a of the studs are preferably inclined toward the pivot 12, as shown in Figs. 2 and 3.

While producing a strong, firm and reliable locking-joint, this construction permits the joints to be easily "broken" or unlocked in folding and unfolding the rule. This construction also affords the further advantages of lightness, neatness and compactness, and enables the joint plates to be made comparatively short without sacrificing stiffness and firmness of the rule-sections when unfolded. This renders the improvement especially desirable for small or vest-pocket rules.

Moreover, the spring-bosses tend to take up wear of the locking studs and openings, and permit the joint plates to be arched to a less degree than without them, relieving the plates and the connecting rivet from undue strain.

The arching of the plates, combined with the spring bosses, also tends to hold the adjoining rule-sections closely together at both ends, when folded, reducing the folded rule to the smallest compass.

I claim as my invention:

1. The combination of a pair of adjoining rule-sections, joint-plates secured to the respective sections and having opposing dished portions forming springs, the concave sides of said dished portions facing each other, and a pivot connecting said plates and passing through said dished portions, the plates being provided with complemental locking devices arranged to interlock in the folded and unfolded positions of the sections.

2. The combination of a pair of adjoining rule-sections, joint-plates secured to the respective sections and having opposing hollow bosses whose concave sides face each other, and a pivot connecting said plates and passing centrally through said bosses, the plates being provided in addition to said bosses with complemental locking devices.

3. The combination of a pair of adjoining rule-sections, joint-plates secured to the respective sections and a pivot connecting said plates, the latter having complemental locking teats and openings located on opposite sides of said pivot, and each plate having a hollow integral boss surrounding said pivot and forming a spring, the concave sides of said bosses facing each other.

4. The combination of a pair of adjoining rule-sections, arched joint plates secured to the respective sections and having opposing dished portions forming springs, the concave sides of said dished portions facing each other, and a pivot connecting said plates and passing through said dished portions, the plates being provided with complemental locking devices.

5. The combination of a pair of adjoining rule-sections, arched joint-plates secured to the respective sections and a pivot connecting said plates, the latter having complemental locking teats and openings located on opposite sides of said pivot and each plate having a hollow integral boss surrounding said pivot and forming a spring, the concave sides of said bosses facing each other.

JAMES H. McCAFFREY.
